DELIVERY VEHICLE SHELF SYSTEM

Filed, Jan. 27, 1930

Jay D. Saville Inventor
By Glenn L. Fish
Attorney

UNITED STATES PATENT OFFICE

JAY D. SAVILLE, OF SPOKANE, WASHINGTON

DELIVERY-VEHICLE SHELF SYSTEM

Application filed January 27, 1930. Serial No. 423,637.

My invention relates to delivery vehicle shelf systems and certain objects of the invention are to provide a shelf system adapted for installation in delivery trucks and 5 other delivery vehicles and which comprises a plurality of spaced shelf units each having lower support and guide means for receiving and retaining the empty shelf sections and upper support and guide means for receiving and retaining said shelf sections for 10 loading. Further objects are to provide a shelf system comprising a plurality of shelf sections that are adapted to be slidably installed and interlocked whereby they may 15 be readily and conveniently loaded and unloaded by slidable means. Other objects are to provide a shelf system having means whereby the assembled or interlocked shelves may be locked or secured against 20 slidable movement, and means for preventing the loaded articles from slipping off of the shelves particularly when unloading.

With the above and other objects in view which will appear as the description proceeds, the invention consists of the novel construction, adaptation, combination and arrangement of parts hereinafter described and claimed. These objects are accomplished by devices illustrated in the accompanying drawings, wherein:—

Figure 1 is a fragmentary view in perspective of a delivery vehicle body showing my shelf system installed therein;

Fig. 2 is a fragmentary top plan view of 35 a shelf unit and showing the interlocking means;

Fig. 3 is a view in longitudinal vertical section taken substantially on a broken line 3, 3 of Fig. 2;

Fig. 4 is a detail view in perspective showing the arrangement of the support and guide rails and locking means on one side; and

Fig. 5 is a like view showing the same 45 elements on the other side.

Referring to the drawings throughout which like reference numerals designate like parts, the numeral 5 indicates the various side rails, a pair of which is provided for 50 each shelf unit. As shown in Fig. 1, each

of said pairs of rails are secured to the interior sides of the vehicle body in horizontally opposite arrangement and in spaced relation and extend substantially the length of said vehicle body. Each of said side rails 55 is provided with a lower runway or flange support 6 and a corresponding upper runway 7. The lower runways are adapted to retain the shelf sections when they are not in use and the upper runways are arranged 60 to support said shelves when they are loaded.

The shelving is made in sections 8 that are arranged to extend transversely across the vehicle body with their end portions 65 slidably resting on the runways 6 or 7. Each of said shelf sections or boards is provided with a strap iron 9 riveted or otherwise secured across its end portion on the underside thereof and each of said straps is 70 provided with an upturned or deflected forward end portion 10 and a rectangular loop 11 on its rear end. A short angle iron 12 is welded or otherwise secured transversely to the forward end portion of said strap 75 irons adjacent their upturned end portions and which angle iron is used to lock the shelves in place and thus prevent them from working forward.

To interlock the shelf sections 8 they are 80 placed transversely of the vehicle with their end portions resting on the runways 6 or 7 and their longitudinal edges in parallel relation as shown in Fig. 3. The loop 11 of each pair of straps 9 fits over the upturned 85 end 10 of the straps secured to the adjacent shelf sections to form a completely assembled shelf. It will be apparent that each 90 complete shelf may be pulled out as a whole and the sections disconnected one at a time, or they may be installed one at a time and connected to form a complete shelf.

Each of the side runways 6 and 7 is provided with a forward upturned end portion 95 13 and to lock each complete or assembled shelf in place same is pulled forward until the angle irons 12 pass over said stationary ends and drop down when same is pushed back until the angle irons engage under said 100

upturned ends as clearly shown in Figs. 4 and 5 of the drawings.

It will now be obvious that I have provided a convenient and compact shelf system comprising a plurality of shelf units placed one above the other and each unit complete within itself. This system is particularly useful in the fact that the lower runways 6 of each unit are adapted for compactly retaining the shelves when not in use and the upper runways are adapted for use in loading the shelves with commodities. The shelves may readily be transferred from the lower to the upper runways or vice versa and the slideable arrangement provides means whereby the shelves may be loaded or unloaded with ease and convenience. Referring to Fig. 1, a head board or upstanding shelf 14 may be secured to either end section of the shelving and will serve to drag the articles out when unloading and prevent them from slipping off as will be understood.

Having thus described my invention, it being understood that minor changes may be resorted to in its construction without departing from the scope and spirit of the invention, what I claim and desire to secure by Letters Patent of the United States is:—

30. 1. A delivery vehicle shelf system comprising a plurality of shelf units disposed in spaced relation one above the other, each of said units comprising a pair of horizontally and oppositely disposed side rails, each of 35 said side rails having an upper and a lower runway, a plurality of shelf sections with their end portions slidably disposed on said runways with their edge portions arranged in adjacent parallel relation, and means for 40 detachably interlocking said shelf sections to form a complete shelf for each unit.

2. A delivery vehicle shelf system comprising a plurality of shelf units disposed in spaced vertical relation, each of said units comprising a pair of horizontally and oppositely disposed side rails, each of said side rails having an upper and a lower runway, a plurality of shelf sections having their end portions slidably disposed on said runways with their edge portions arranged in adjacent parallel relation, means for detachably interlocking said shelf sections to form a complete shelf unit, and means for locking said complete shelf units to prevent slipping.

3. A delivery vehicle shelf system comprising a plurality of shelf units arranged in vertical spaced relation, each of said units comprising a pair of horizontally and oppositely disposed side rails, each of said side rails having an upper and a lower runway, a plurality of shelf sections having their ends slidably disposed on said runways with their edges arranged in adjacent parallel relation, means for detachably interlocking

said shelf sections to form a complete shelf unit, means for locking said shelf units against slideable movement, and a head board for the end shelf sections.

In testimony whereof I affix my signature.

JAY D. SAVILLE.
